US0D1067947S

(12) **United States Design Patent** (10) **Patent No.:** **US D1,067,947 S**
(45) **Date of Patent:** **** Mar. 25, 2025**

(54) **PADDLE PUMP**

(71) Applicant: **Dongguan Hang Che Bao Future Technology Co., Ltd.**, Dongguan (CN)

(72) Inventor: **Guofa Zeng**, Loudi (CN)

(73) Assignee: **Dongguan Hang Che Bao Future Technology Co., Ltd.**, Dongguan (CN)

(**) Term: **15 Years**

(21) Appl. No.: **29/953,589**

(22) Filed: **Jul. 23, 2024**

(51) LOC (15) Cl. **15-02**

(52) U.S. Cl.

USPC **D15/7**; D15/9

CLAIM

The ornamental design for a paddle pump, as shown and described.

DESCRIPTION

FIG. 1 is a first perspective view of a paddle pump showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the paddle pump that form no part of the claimed design.

1 Claim, 8 Drawing Sheets
